(57) **CLAIM**

The ornamental design for a toilet seat and cover, as shown and described.

DESCRIPTION

FIG. 1 is a front perspective of a toilet seat and cover combination.

FIG. 2 is a rear perspective thereof.

FIG. 3 is a top plan view thereof.

FIG. 4 is a left side elevational view thereof; the right side view being a mirror image of that shown.

FIG. 5 is a front elevational view thereof.

FIG. 6 is a rear elevational view thereof.

FIG. 7 is a cross-section taken along line 7—7 in FIG. 3.

FIG. 8 is a front perspective view of the seat portion with the cover portion lifted; and,

FIG. 9 is a top plan view thereof.

The broken line showing of parts of the underside of the seat, the underside of the lid, and the hinges is for illustrative purposes only and forms no part of the claimed design. In addition, the portions of the seat and cover not shown are not part of the claimed design.
